UNITED STATES PATENT OFFICE

CONRAD J. FRÜH, OF ZURICH, SWITZERLAND

PROCESS FOR WET-TREATMENT, ESPECIALLY FOR WASHING TEXTILE GOODS IN THE FORM OF FABRICS

Application filed August 8, 1931, Serial No. 556,006, and in Germany June 6, 1929.

An application has been filed in Germany June 6, 1929.

The present invention relates to an apparatus for wet-treatment, especially for washing textile goods in the form of fabrics.

The main object of this invention is to provide an apparatus with a porous band immersed in the washing liquid, taking the textile goods along in a plaited form and dipping it more or less into the liquid, according to the kind of the fabric, whereby the latter is sprinkled from above with the same liquid at the same time.

A further object of my invention is to provide means for changing the depth of immersion and the sprinkling surface of the fabric.

My invention will be best understood when described in connection with the accompanying drawings in which Figs. 1 and 1a show a longitudinal section, Fig. 2 a partial cross section, Figs. 3 and 4 show different ways of conducting the fabric.

1 designates a tub for the washing liquid, 2 shows uprights placed partly inside, partly outside the tub 1. To the uprights 2 traverses 3 and 5 are connected, carrying the chains 6 of the band 7 and also the bearing 8 for the reel-shafts 9. On the traverses 3 bearings 10 are mounted, taking up shafts 11, 11', upon which chain wheels 12 driving the chain 6 are fixed. The shaft 11 carries a chain wheel 13, actuated in a well known manner by the driving parts, viz. chain 14, chain-wheel 15, speed reduction parts 16, 17 and 18 and which serves for the drive of the chain 6 and the band 7.

Upon the shafts 8 reels 20 are placed, showing dented rims and engaging with pinions 22 sitting fast on a shaft 24, lodged in bearings 23 together with a driving pulley 25, the latter thus being able to cause the reels to rotate.

In order to be able to regulate the stretch in all the parts of the fabric, each reel 20 is provided with a coupling, comprising coupling rings 26, 27, a lever 28 and a bracket 29. The whole frame of the machine is strengthened by traverses 30.

There are tubes 31 provided on each side of the tub 1, relied together by liquid delivery tubes 32 which serve to sprinkle the fabric with washing liquid during its passage in the direction of the arrow. Thereby the sprinkling medium can be taken from the tub 1 either by means of the tubes 33 or the net of tubing 34, 35, and conveyed to the tubes 31 by means of a (not shown) pump. It goes without saying that the liquid delivery tubes can also be connected to any freshwater-conduit.

In order to be able to change the depth of immersion and the sprinkling surface of the fabric an overflow 36 is provided, by turning of which, as indicated by the arrow, the depth of the liquid can be regulated.

Fig. 3 shows schematically the introduction of the fabric into the machine by means of a feeding-device E.

Fig. 4 shows schematically the treatment of the fabric in three steps.

The working of the apparatus is as follows:

The textile goods are placed at least once upon the band in a widely spread form by the reels, the band then, due to its low speed takes the fabric along steadily and in a plaited form, the fabric, during the motion being thoroughly soaked with washing liquid. Thereby the level of the liquid, regulated by means of the overflow is higher than the band. The fabric thus dips into a washing liquid adjustable in height and is sprinkled at the same time with the same liquid from above. The fabric being sustained in the fluid can not be compressed by the pressure of the fluid issuing the jets as the water in the tank whose level is regulated according to the width of the pleats receives the impact of the water from the jets, whereas those portions of the pleats above the level of the water in the tank are sustained or partially supported by the fluid in the tank.

By this way I have the advantage of a thorough soaking of the textile goods with washing liquid whereby the fabric being moved slowly in a plaited form can stretch and shrink in any direction.

In order that the textile goods may not

remain in the same plaits during the whole process, it can be taken off the band by means of one or more reels and replaced on it afresh.

The last reel pulls the fabric away from 5 the apparatus.

What I claim is:

The method of washing fabric in the piece which consists in forming a series of loose plaits in the fabric, partially immersing the 10 plaited fabric in a washing bath in such man-

ner that the upper portions of the plaits project above the bath whereby the fabric is substantially supported by the floatative effect of the bath, moving the fabric in its plaited condition through the bath without producing pressure on or tension in the fabric, and simultaneously with said movement sprinkling the portions of the plaits projecting above the bath. 70
